(57) **CLAIM**

The ornamental design for a lumbar pillow, as shown and described.

DESCRIPTION

FIG. 1 is a first perspective view of a lumbar pillow showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 2;

FIG. 10 is a perspective view of another state of the lumbar pillow thereof;

FIG. 11 is a perspective view of another state of the lumbar pillow thereof; and,

FIG. 12 is a perspective view of another state of the lumbar pillow thereof.

The broken lines shown in the drawings depict portions of the lumbar pillow that form no part of the claimed design. The dot-dash broken lines in FIGS. 1 and 9 depict boundary lines of the enlargement views and form no part of the claimed design.

1 Claim, 12 Drawing Sheets
